UNITED STATES PATENT OFFICE.

CHARLES A. HINSDILL, OF TROY, NEW YORK.

DESIGN FOR AN ELECTRIC-LIGHT-FIXTURE BRACKET.

46,737.

Specification for Design.

Patented Dec. 8, 1914.

Application filed February 12, 1914. Serial No. 818,413. Term of patent 14 years.

To all whom it may concern:

Be it known that I, CHARLES A. HINSDILL, a citizen of the United States, residing at Troy, in the county of Rensselaer and State of New York, have invented a new, original, and ornamental Design for Electric-Light-Fixture Brackets, of which the following is a specification, reference being had to the accompanying drawing, forming part thereof.

The single figure of the drawing is a view in perspective of an electric-light fixture-bracket, showing my new design.

I claim:

The ornamental design for an electric-light fixture-bracket substantially as shown.

CHARLES A. HINSDILL.
